POWER TUBE STRUCTURE

Charles V. Litton, Redwood City, Calif., assignor to International Standard Electric Corporation, New York, N. Y., a corporation of Delaware

Application June 6, 1942, Serial No. 446,034

7 Claims. (Cl. 250—27.5)

This invention relates to vacuum tubes and more particularly to high power vacuum tubes such as are used in radio transmitters.

Vacuum tubes have been constructed in small sizes in which the filaments have a very high electron emission and the anodes are so constructed as to dissipate the heat generated by the electron stream and thus to have a larger power capacity than would otherwise be achieved. The technique of these smaller vacuum tubes, however, is not generally applicable for use in the large high power vacuum tubes.

It is the principal object of my invention to produce a high power vacuum tube having a large electron emission and an anode capable of dissipating the heat generated by the resulting electron high current without requiring that the vacuum tubes be of the large dimensions previously necessary for such power tubes.

According to one feature of my invention I provide a high emissive filamentary cathode divided into sections so that excessive filament sag will not occur and envelop this cathode structure by an anode provided with liquid cooling means and so constructed that a relatively large temperature gradient between the internal surface of the anode and the cooling medium is achieved.

A better understanding of my invention and the objects and features thereof may be had from a reading of the particular description of my invention made with reference to the accompanying drawings in which

Fig. 1 is a view of a vacuum tube in accordance with my invention partly in section to show the construction;

Fig. 2 is an alternative anode arrangement for use in a tube such as shown in Fig. 1;

Fig. 3 is a diagram explaining the operation of a metallic body in dissipating heat;

Fig. 4 is a view illustrating the structure of the cathode in accordance with my invention; and

Figs. 5 and 6 are simplified illustrations showing the electrical relationship of filaments in a cathode structure such as shown in Fig. 4.

Turning first to Fig. 1, 10 indicates a filamentary cathode of high electron emission. This cathode is preferably made of thoriated tungsten and is wound quadrifilar so that alternate windings of the spiral carry current flowing in opposite directions. A more particularly description of the cathode construction will be given later in connection with Figs. 4, 5 and 6.

Numerals 11 designates a grid of any desired known structure arranged around cathode 10.

Arranged about cathode 10 and grid 11, and substantially enveloping it, is the anode of the tube comprising a metallic shell portion 12 on which are provided raised portions or projections 13. Contacting these raised portions 13 is wound a spiral coil 14 made up of hollow tubular member 15. Certain parts of this tube are in direct conductive connection with the projecting portion 13 of shell 12, and the other portions are in direct conductive connection with the other turns of the tube or pipe 15. Thus, a continuous metallic conductive path from the inner surface of shell 12 to the outer atmosphere is provided. In tubular members 15 is circulated a cooling liquid, preferably water.

The particular structure illustrated in Fig. 1 enables a great amount of heat to be dissipated from the internal surface of anode shell 12 so that the tubes may operate at a much higher concentration of energy than a conventionally built tube of the same size. The reason for this may be better understood by a brief reference to Fig. 3 in which a metallic member 30 is shown. This member 30 has applied to it heat on the under surface, points 31 and 35 of which may be considered as representing unit areas or specific points of a continuously heated sheet. As the heat from point 31 travels outwardly through the metal, it tends to spread along the metal as indicated by lines 32 and 33. It is, therefore, clear that if the metal is made thicker as it is at point 35, a greater spread will occur, as shown at 36, 37. Where the metal is relatively thin, as at point 31, a tremendous temperature gradient must be maintained between the heating point 31 and the outer surface of the metal if a large amount of cooling is desired. If water cooling is used this means that a huge volume of water must be circulated over the surface in order to dissipate the heat, since the heat transfer can take place over only a relatively narrow surface of water. Thus, if water cooling is provided, a large circulation of water must be provided in order that sufficient water contacts point 13 to maintain the proper cooling. The volume of water which can be circulated effectively is also limited since at the higher velocities the water will not as thoroughly wet the surface and therefore will not provide for efficient heat transfer.

By use of a thicker section of metal as indicated at point 35, the area over which heat transfer to the water may take place is greatly increased. Likewise, because of the added thickness of metal a smaller temperature gradient need exist within

the metal in order that the same amount of heat may be transferred. In the anode of a vacuum tube, therefore, it is clear that greater heat dissipation could be achieved by making the anode of thick, heavy metal. This, however, adds greatly to the cost and weight of the tube.

In accordance with my invention the advantages of a thick metal portion may be obtained without the necessity of making the walls of solid, thick metallic portions. This is accomplished as shown in Fig. 1 by having the metallic pipe in which the circulating water is carried in direct conductive connection with the inner shell 12 of the anode. Thus, the temperature gradient from the center of the shell to the cooling medium may be relatively low because of the long conductive path. Furthermore, the heat will be conducted entirely around the cooling water so that a large cooling surface is presented. It can be seen that if projections are provided as shown in Fig. 1, the path extends not only from the inner surface of the shell 12 but up through these projections 13 and the walls of tube 15. Accordingly, an extremely efficient heat transfer is accomplished and the anode may therefore be operated at a much higher temperature. Accordingly, a smaller tube structure may be operated to produce higher output currents since the heating of the anode usually is the limiting factor in the power handling capacity of the tube.

In Fig. 2 an alternative structure to that shown in Fig. 1 for the anode is shown. In this arrangement the shell 12 is not provided with projections. Tube members 25 are provided and are directly in contact with the outer surface of shell 12. As shown in this figure the tubes are made square in form so that a larger surface thereof will be in contact with the outer wall of shell 12. By this arrangement a continuous conductive heat path is provided from the inner wall of shell 12 through the walls of tube 25, and thus an efficient heat transfer to the cooling medium circulating in the tube 25 is provided.

Although Figs. 1 and 2 illustrate two alternative arrangements of the anode it should be understood that these are merely two of many examples which may be constructed within the teachings of my invention.

In Fig. 4 is shown a structural arrangement of a filamentary cathode 10 made to produce high current emission. The high current emitting cathode is desirable in order that sufficient emission to permit operation of the tube at its rated higher capacity may be achieved.

In the structural example given, the central supporting rod 40 is provided and on this rod are fixed discs 41, 42, 43, as indicated. Two current supply lines 44, 45 extend through insulating openings in discs 41 and 42 up to a point just beyond disc 42. A first filamentary cathode arrangement comprising four separate spiral windings 46, 47, 48 and 49 is provided between discs 41 and 42. Windings 46 and 47 are connected together at their ends adjacent disc 42 and are connected to feeding conductor 44. Similarly, windings 47 and 49 are connected together at their ends and fastened to feeder line 45. At their other end all of conductors 46, 47, 48 and 49 are fastened to the disc 41.

Similarly the other windings comprising four conductors 51, 52, 53 and 54, are all connected to disc 43 and windings 51 and 53 are connected

together to conductor 44, while 52 and 54 are connected together to conductor 45.

A better showing of the interconnection of the windings of Fig. 4 may be had by reference to the simplified circuit arrangement shown in Fig. 5.

It is clear that while the structural arrangement of Fig. 4 has been illustrated the filamentary cathode in accordance with my invention need not be limited to two such quadrifilar wound units. If desired the windings may be multiplied in number. For example, in Fig. 6 there are shown four units connected together as in Fig. 5. The first two unit arrangements may be identical to those shown in Fig. 5 and accordingly the same reference characters have been applied thereto. Conductors 44, 45, however, continue upwardly beyond a further disc 65. Further still is provided another disc 66. Two additional sets of windings 56, 57, 58, 59 and 61, 62, 63 and 64, corresponding to 46 to 48 and 51 to 54, inclusive, are arranged end to end with the other pair of windings. These windings are connected together similarly to conductors 44 and 45 so that the entire system is fed in parallel. It should be understood that the separate units each comprise four spiral wound conductors as shown in Fig. 4.

It is further clear that this extension may be continued to include as many cathode units as is desired. For example, if it is not desired to use four but to use three units this may be accomplished merely by omitting the top set of windings 61 to 64, and terminating the cathode at disc 65. Furthermore, if it is desired, separate pairs of lead-in conductors may be connected in parallel at the lower end and brought into the junction point between any two units instead of using the single conductor pair as shown in the simplified form of Fig. 6.

By using short units of the form illustrated in the drawing, the filaments may be heated to a high temperature but because of the shortness of the spirals will not sag and cause distortion and possible short circuits in the tube. By the use of this arrangement the entire filament structure may be made as long as desired without weakening the cathode as a whole and without increasing the danger of short circuiting or sagging.

While I have specifically described particular examples of my invention it should be understood that many changes may be made within the scope of my invention without departing from the spirit thereof.

It should also be appreciated that the features of my invention may be applied to various types of vacuum tubes differing considerably in construction and appearance from the disclosures made herein. The specific examples shown are not intended as a limitation on the scope of my invention but merely as specific practical working examples thereof.

What is claimed is:

1. A vacuum tube comprising a cathode, a control grid arranged about said cathode, and an anode, said cathode comprising a plurality of spiral quadrifilar wound filamentary cathode units positioned end to end, means for connecting in each unit the windings in series parallel connection so that current flows in opposite directions in adjacent turns of said spirals, the series connected ends of the windings being connected to a common point, means for feeding said units in parallel with respect to one an-

other, and means for mechanically supporting said units, said anode comprising a metallic shell surrounding said cathode and grid and means for developing a relatively low temperature gradient within the metal between the internal surface of said shell and a cooling medium including liquid carrying metallic pipes wound about said shell and in direct thermal contact therewith.

2. A high power vacuum tube according to claim 1, wherein said anode metal shell is provided with externally projecting portions to further extend the metallic thermal path to further lower the temperature gradient, said metallic tubing being in conductive contacting relation with said projections.

3. A vacuum tube cathode comprising a plurality of spiral quadrifilar wound filamentary cathode units positioned end to end, means for connecting in each unit the windings in series parallel connection so that current flows in opposite directions in adjacent turns of said spirals, the series connected ends of the windings being connected to a common point, means for feeding said units in parallel with respect to one another, and means for mechanically supporting said units.

4. A vacuum tube filamentary cathode comprising a pair of feeding conductors, a central supporting rod, discs fixed to said rod at predetermined spaced intervals, at least two filamentary units positioned end to end, each comprising four spiral conductors forming a quadrifilar filament winding, one end of said spirals all be-

ing connected together at one of said discs, the other ends of said spirals being connected in pairs to respective ones of said feeding conductors.

5. A vacuum tube filamentary cathode comprising a pair of feeding conductors, discs fixed at predetermined spaced intervals, at least two filamentary units positioned end to end, each comprising four spiral conductors forming a quadrifilar filament winding, one end of said spirals all being connected together at one of said discs, the other ends of said spirals being connected in pairs to respective ones of said feeding conductors.

10 6. A vacuum tube according to claim 5, where-
15 in four end to end filamentary units are provided, the adjacent ends of the two centrally positioned units being connected to a common disc, further comprising heat shield discs insulated from said filamentary units arranged between units
20 at the ends connected to said feeding conductors.

25 7. An anode for a vacuum tube having a cathode and a control grid surrounding the cathode said anode comprising a metallic shell surround-
30 ing said cathode and grid means for developing a relatively low temperature gradient within the metal between the internal and external surfaces of said shell, including raised portions formed on said metallic shell on the external surface thereof, and a cooling means including liquid carrying metallic pipes wound about said shell and in direct thermal contact with the raised portions on said shell.

CHARLES V. LITTON.
